Ernest Fischer

By his Attorney
Marvin E. Klein

UNITED STATES PATENT OFFICE.

ERNEST FISCHER, OF NEW YORK, N. Y.

DISPLAY EASEL.

Application filed March 26, 1925. Serial No. 18,345.

To all whom it may concern:

Be it known that I, ERNEST FISCHER, a citizen of the United States, residing at New York, in the county of New York and State 5 of New York, have invented certain new and useful Improvements in Display Easels, of which the following is a specification.

This invention relates to improvements in easels and particularly to types in which a 10 pair of photographs or the like may be simultaneously displayed.

One of the objects of the invention is to provide an easel composed of two rigid plates connected integrally by a flexible member, 15 each plate having a single opening centrally therein, and capable of being folded together.

Another object is to provide a substantially nonbreakable, transparent shield at 20 each opening through which the photograph may be viewed.

A further object is to provide a base or support by which the easel is held at a desirable angle, this support being hollow and 25 having a chamber in which the folded easel may be wholly disposed at will.

These and other objects, such as the provision of means to render the hollow base dust-proof, to raise the easel into position for 30 ready removal, and to provide a neat and artistic device for the purpose, are attained by the novel construction and combination of parts hereinafter described and shown in the accompanying drawing, forming a material part of this disclosure, and in which:—

Figure 1 is a perspective view of an embodiment of the invention as erected for display.

Figure 2 is a similar view of the same as 40 folded for storage or carriage.

Figure 3 is a transverse sectional view of the same drawn to an enlarged scale.

Figure 4 is a fragmentary sectional view 45 thereof, showing the easel in an extended position.

Figure 5 is a fragmentary face view of the easel in detail.

Referring more in detail to the drawing, 50 the numeral 10 designates the body of the hollow base, the same being made to resemble

the appearance of a conventional type of book, and having a leaf or lid 11 engaged at the outer edge by a hinge 12, as a strip of textile fabric.

This lid is provided with a flexible pull 13, 55 and may be held when closed by pivoted buttons 14 in the lid near the back of a book, is a longitudinal slot 15, provided with a flap or cover 16 to close against the inner side, this flap being attached by a flexible 60 hinge 17.

The easel is composed of two substantially rectangular plates 18 having a flexible connecting strip 19 acting as a hinge, and each plate contains an opening 20 at the front, 65 here shown as oval, adjacent to which is a transparent plate 21, as celluloid, the same being entered through a slit 22 in the top of the plate, this slit also being receptive of the object to be displayed. 70

Each plate contains notches 23 in the bottom edge, their adjacent edges being bevelled and the portion between the notches, including the flexible strip, is adapted to be entered in the slot 15, displacing the flap 16 75 and to rest upon the inner, lower front corner of the base to stand at a slight angle as best in Figures 1 and 4.

The adjacent edges of the notches 23 are convergently inclined as they approach the 80 bottom of the plates, to make contact with the ends of the slot 15, thus centering the easel upon its base.

At the back of the easel is a strip 24 constituting a pocket to retain papers or the 85 like, the strip being attached at its end 25 only.

A tape 26 is secured within the hollow base at one end 27, see Figures 3 and 4, and at the bottom end to the lid at 28, this tape 90 acting to raise the folded easel from the interior of the base automatically upon raising the lid.

Having thus described my invention, what I claim as new and desire to secure by Letters Patent, is:—

An easel having a chambered base containing an elongated slot contiguous to one of its longer side edges, a lid hinged at the opposite edge, a flap hinged in said base to 100

normally cover the mentioned slot, a support plate composed of two sections flexibly united and foldable to enter the chamber in said base, said plate having a notched lower edge, the portion between the notches being disposable in the mentioned slot to rest upon the bottom wall of said chamber when

erected on the base to be firmly held thereon, and transparently covered openings in said plate receptive of articles to be displayed. ¹⁰

In witness whereof I have affixed my signature.

ERNEST FISCHER.
